LOCKING OR HOLDING CATCH.

1,255,363.

Specification of Letters Patent.

Patented Feb. 5, 1918.

Application filed February 27, 1917. Serial No. 151,162.

To all whom it may concern:

Be it known that I, BENNO VON EIGEN, a citizen of the United States, residing at Newark, in the county of Essex and State of New Jersey, have invented certain new and useful Improvements in Locking or Holding Catches; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention has reference, generally, to improvements in catches; and, the present invention relates, more particularly, to a novel and simply constructed locking or holding catch which is especially adapted for use with portfolios, music-rolls, pocket-books, bags, trunks, suit-cases, and the like.

20 The present invention, therefore, has for its principal object to provide a novel, effective and simply constructed locking or holding catch of the general character herein-after set forth, in which the parts are reduced to a minimum, and in which the hasp-plate is made in the form of a hingeless element and is suspended in its operative relation to the remaining parts of the catch without the use of rivets, screws, or similar fastening devices.

25 The present invention has for its further object the novel arrangement and construction of a spring mounted within a box-like element or shell for operatively securing the hasp-plate in its suspended position and at the same time rendering the said plate spring-actuated and spring-controlled.

30 Other objects of the invention not at this time more particularly enumerated will be clearly understood from the following detailed description of the same.

35 With the various objects of the present invention in view, the said invention consists, primarily, in the novel locking or holding catch hereinafter more fully set forth; and, the invention consists, furthermore, in the novel arrangements and combinations of the various devices and parts, as well as in the details of the construction of the said parts, all of which will be more fully described in the following specification, and then finally

embodied in the clauses of the claim which are appended to and which form an essential part of the said specification.

55 The invention is clearly illustrated in the drawings, in which:

Figure 1 is a front face view of a locking or holding catch showing one embodiment of the principles of the present invention, and illustrating the separable members of the catch secured to the separable members of a portfolio, or other suitable receptacle, as a bag, suit-case, trunk, or the like; and Fig. 2 is a side elevation of the said locking or holding catch with the members which are to be locked by means of the catch being shown in vertical section.

Fig. 3 is a sectional representation of the various devices and parts of the catch, said section being taken on line 3—3 in said Fig. 1, looking in the direction of the arrow *x*, said view being also made on an enlarged scale.

75 Fig. 4 is a rear view, on an enlarged scale, of the upper box-like member or shell of the catch, and of the hasp-plate suspended therefrom with the spring for operatively retaining the said parts in their assembled relation, the lower part of the hasp-plate being shown broken away; and Fig. 5 is a horizontal sectional representation, said section being taken on line 5—5 in said Fig. 1, and said view being also made on an enlarged scale.

80 Similar characters of reference are employed in all of the said above described views, to indicate corresponding parts.

85 Referring now to the several figures of the drawings, the reference-characters 1 and 2 indicate fragmentary portions of two members of a portfolio, music-roll, pocket-book, bag, trunk, suit-case, or the like, which are to be brought into locked relation by means of the holding or locking catch.

90 The holding or locking catch which embodies the principles of the present invention comprises two box-like elements or shells, as 3 and 4, the lower element 3 being adapted to be secured to the member 1 by means of rivets 5, or other suitable fastening means, and the upper element 4 being adapted to be secured to the member 2 by means of rivets 6, or other suitable fastening means.

100 105 The said lower element 3 which may be of

any suitable configuration, but which is preferably of a rectangular configuration, as here shown, is made in the form of a chambered shell or box, the face-plate of which is 5 rounded by the marginal flanges or edges 7. Within the chamber 8 provided by said shell or box of the lower element 3 is suitably secured by means of rivets 9, as indicated in Figs. 1 and 2, or otherwise secured therein, 10 a suitable lock-mechanism, the upper portion of the casing 10 of which, as will be seen from an inspection of Fig. 3 of the drawings, being represented in section. The reference-character 11 indicates, also in section, 15 the movably disposed hasp-post engaging plate or bolt of the lock-mechanism, and 12 indicates a suitable operating device or fingerpiece slidably disposed upon the outer face of the said lower box or shell 3 and 20 operatively connected in any usual manner with the hasp-post engaging plate or bolt 11 of said lock-mechanism. The face-plate of the said box or shell 3 is provided with a suitably disposed perforation, as 13, and the 25 casing 10 of the lock-mechanism is provided with a correspondingly disposed perforation, as 14, for the reception of a hasp-post, in the manner shown in Fig. 3 of the drawings, the operation of which and its purpose 30 will be presently more fully described.

The face-plate of the shell or box 3 is also provided with a key-receiving hole or opening, as 15, for the insertion of a key and to immovably lock the parts of the lock-mechanism in the usual manner when so desired.

The upper element 4, herein-above mentioned, may also be of any suitable configuration, preferably of the rectangular configuration here shown, and the same is made in 40 the form of a chambered shell or box, the face-plate of which is surrounded by the marginal flanges or edges 16.

In its face-plate, the said upper shell or box 4 is provided with a horizontally disposed and outwardly and upwardly projecting supporting member, as 17, and a horizontally disposed opening, as 18, located directly above the said member 17. As shown in the accompanying drawings, the said supporting member 17, for the proper pivotal support or suspension of the hasp-plate, to be presently described, is a long rib or projection, while the opening 18 is a correspondingly long slit. Extending from the upper 50 marginal flange or edge 16 inwardly into the chamber 19 provided by said shell or box 4 are suitable retaining ears or lugs, as 20.

The reference-character 21 indicates a hasp-plate of any suitable marginal configuration, the said hasp-plate being formed at its upper edge-portion with a rearwardly and slightly downwardly extending marginal lip or projection as 22, providing an angular means of suspension resting pivotally upon the marginal edge 23 of the above-

mentioned supporting member or rib 17, substantially as shown. The said means of suspension 22, as will be seen from Figs. 3, 4 and 5 of the drawings, is made with an elongated opening or slot, as 24, into and 70 through which extends the V-shaped central portion 25 of a torsion spring, the respective end-members 26 of which are bent suitably as shown, and are sprung into holding retaining engagement with the flange 16, directly beneath the said ears or lugs 20, and with the V-shaped central portion 25 of the spring bearing positively upon the inner surface of the face-plate of the box or shell 4, as clearly shown in Figs. 3 and 4 of the drawings. The result of this torsional action of the said spring, under normal initial conditions, is to cause the hasp-plate to swing outwardly and stand in its unlocked relation, indicated in the dotted outline in said 85 Fig. 3.

To bring the said hasp-plate into its proper locked relation, when depressed in the direction of the arrow y, see said Fig. 3, the said plate is preferably curved, as at 27, 90 and upon its lower end-portion the plate has a rearwardly projecting hasp-post or locking stud, as 28, which enters the previously-mentioned perforations 13 and 14, and is engaged by the lock-mechanism-controlled 95 hasp-lug engaging plate or bolt 11. As soon as the said plate or bolt 11 is withdrawn from its holding engagement with the said post or stud 28, the torsion spring within the shell or box 4 again causes the hasp-plate to 100 assume its disengaged and unlocked relation with the lower shell or box 3, as will be evident.

From the foregoing description of the present invention it will be clearly evident that I have devised a simply constructed and neat catch, in which the parts are easily and quickly assembled, and in which the usual hinge-ears and pintles are entirely dispensed with, and a device is made which can be more readily and cheaply manufactured, and is not likely to get out of order.

Of course I am aware that changes may be made in the general arrangements and combinations of the several devices and parts, as well as in the details of the construction of the said parts, without departing from the scope of the invention as set forth in the foregoing specification and as defined in the clauses of the claim which are appended thereto. Hence, I do not limit my present invention to the exact arrangements and combinations of the several devices and parts as described in the said specification, nor do I confine myself to the exact details 120 of the construction of the said parts as illustrated in the accompanying drawings.

I claim:

1. A catch comprising an upper chambered element and a lower element, said 130

- upper element having a slotted face-plate, a hasp-plate provided with a rearwardly extending means of suspension projecting through the slit of said face-plate and extending into the chamber of said upper element so that the hasp-plate is suspended from said upper element, a non-riveted spring entirely within the chamber of said upper element, said spring having a portion in engagement with said means of suspension, and means connected with said lower element with which the said hasp-plate is adapted to be brought into locked engagement.
- 15 2. A catch comprising an upper chambered element and a lower element, said upper element having a slotted face-plate providing a means of support, a hasp-plate provided with a rearwardly extending marginal lip projecting through the slit of said face-plate and extending into the chamber of said upper element and resting upon said means of support so that the hasp-plate is suspended from said upper element, said marginal lip being provided with an opening, a non-riveted spring entirely within the chamber of said upper element having portions in engagement with the inner surface of said face-plate and said spring extending into and being passed through the opening in said lip, and means connected with said lower element with which the said hasp-plate is adapted to be brought into locked engagement.
- 30 35 3. A catch comprising an upper chambered element and a lower element, said upper element having a slotted face-plate and an outwardly extending rib-like supporting member located beneath the slit in said face-plate, a hasp-plate provided with a rearwardly extending marginal lip projecting through said slit of said face plate and extending into the chamber of said upper element and resting upon said supporting member so that the hasp-plate is suspended from said upper element, said marginal lip being provided with an opening, a spring within said upper element having portions in engagement with the inner surface of said face-plate and said spring extending into and being passed through the opening in said lip, and means connected with said lower element with which the said hasp-plate is adapted to be brought into locked engagement.
- 40 45 50 55 60 65 4. A catch comprising an upper and a lower element, said elements being surrounded by rearwardly extending marginal flanges, retaining lugs extending inwardly from one of the marginal flanges of said upper element, said upper element having a slotted face-plate and an outwardly extending rib-like supporting member located beneath the slit in said face-plate, a hasp-plate provided with a rearwardly extending marginal lip projecting into said slit and resting upon
- said supporting member so that the hasp-plate is suspended from said upper element, said marginal lip being provided with an opening, a V-shaped spring within said upper element, said spring extending into and being passed through the opening in said lip and having the apex of said spring in contact with the inner surface of the face-plate of said upper element and the shank-portions of said spring being in retained engagement with said retaining lugs, and means connected with the lower element with which said hasp-plate is adapted to be brought into locked engagement.
- 75 5. A catch comprising an upper chambered element and a lower element, said upper element having a slotted face-plate, a hasp-plate provided with a rearwardly extending means of suspension projecting through the slit of said face-plate and extending into the chamber of said upper element so that the hasp-plate is suspended from said upper element, a non-riveted spring entirely within the chamber of said upper element, said spring having a portion in engagement with said means of suspension, and a hasp-post extending rearwardly from the lower portion of said hasp-plate, combined with a lock-mechanism within said lower element, and a hasp-post engaging bolt connected with said lock-mechanism and adapted to be engaged by the hasp-post of the hasp-plate.
- 80 85 90 95 100 105 110 115 120 125 130 6. A catch comprising an upper chambered element and a lower element, said upper element having a slotted face-plate providing a means of support, a hasp-plate provided with a rearwardly extending marginal lip projecting through the slit of said face-plate and extending into the chamber of said upper element and resting upon said means of support so that the hasp-plate is suspended from said upper element, said marginal lip being provided with an opening, a non-riveted spring entirely within the chamber of said upper element having portions in engagement with the inner surface of said face-plate and said spring extending into and being passed through the opening in said lip, and a hasp-post extending rearwardly from the lower portion of said hasp-plate, combined with a lock-mechanism within said lower element, and a hasp-post engaging bolt connected with said lock-mechanism and adapted to be engaged by the hasp-post of the hasp-plate.
7. A catch comprising an upper chambered element and a lower element, said upper element having a slotted face-plate and an outwardly extending rib-like supporting member located beneath the slit in said face-plate, a hasp-plate provided with a rearwardly extending marginal lip projecting through said slit of said face plate and extending into the chamber of said upper element and resting upon said supporting member so that the

4
hasp-plate is suspended from said upper element, said marginal lip being provided with an opening, a spring within said upper element having portions in engagement with the inner surface of said face-plate and said spring extending into and being passed through the opening in said lip, and a hasp-post extending rearwardly from the lower portion of said hasp-plate, combined with a lock-mechanism within said lower element, and a hasp-post engaging bolt connected with said lock-mechanism and adapted to be engaged by the hasp-post of the hasp-plate.

8. A catch comprising an upper and a lower element, said elements being surrounded by rearwardly extending marginal flanges, retaining lugs extending inwardly from one of the marginal flanges of said upper element, said upper element having a slotted face-plate and an outwardly extending rib-like supporting member located beneath the slit in said face-plate, a hasp-plate provided with a rearwardly extending marginal lip projecting into said slit and resting upon

said supporting member so that the hasp-plate is suspended from said upper element, said marginal lip being provided with an opening, a V-shaped spring within said upper element, said spring extending into and being passed through the opening in said lip and having the apex of said spring in contact with the inner surface of the face-plate of said upper element and the shank-portions of said spring being in retained engagement with said retaining lugs, and a hasp-post extending rearwardly from the lower portion of said hasp-plate, combined with a lock-mechanism within said lower element, and a hasp-post engaging bolt connected with said lock-mechanism and adapted to be engaged by the hasp-post of the hasp-plate.

In testimony, that I claim the invention set forth above I have hereunto set my hand this 23rd day of February, 1917.

BENNO VOM EIGEN.
